UNITED STATES PATENT OFFICE.

CHARLES M. ROLLO, OF SHAWNEE, OKLAHOMA, ASSIGNOR OF ONE-HALF TO LAMAR McDANIEL, OF SHAWNEE, OKLAHOMA.

SIGNALING OR INDICATING BUOY.

1,196,588.

Specification of Letters Patent. Patented Aug. 29, 1916.

Application filed January 18, 1916. Serial No. 72,814.

To all whom it may concern:

Be it known that I, CHARLES M. ROLLO, a citizen of the United States, residing at Shawnee, in the county of Pottawatomie and State of Oklahoma, have invented new and useful Improvements in Signaling or Indicating Buoys, of which the following is a specification.

This invention relates to a signaling or indicating buoy designed for use upon submarine or other vessels, whereby in the event of the inability of the submarine to rise to the surface, or the sinking of an ordinary vessel, a buoy will or may be sent to the surface to indicate the position of the vessel and to serve as a medium for carrying written or other signals to the surface, if desired.

A further object of the invention is to provide an indicating or signaling buoy adapted for use upon a submarine or ordinary vessel, which is normally fastened in a secure manner to the vessel by fastening means and is also connected with the vessel by means of a cable adapted to unwind from a drum, whereby when desired the buoy may be released so as to rise to the surface, the cable paying out and serving as a means for preventing the buoy from drifting away and as a medium whereby the position of the vessel upon the bottom may be determined.

The invention consists of the features of construction, combination and arrangement of parts herein fully described and claimed, reference being had to the accompanying drawings in which:—

Figure 1 is a view illustrating the use of the device upon a submarine boat. Fig. 2 is a side elevation showing the device as normally supported upon the vessel. Figs. 3 and 4 are opposite end elevations of the same.

Referring to the drawings, 1 designates a buoyant body, comprising an air tight barrel or drum, having chines or end flanges 2 and supporting bracket pieces 3. The body 1 may be provided with an opening 4 sealed normally by an air tight door or closure 5, so that when desired written messages or other articles may be placed within the barrel or drum to be carried to the surface from the sunken vessel. The drum is normally supported upon the vessel within a receiving cradle 6 formed by a partially

circular upper end portion 7 of frame standards or legs 8, having angularly bent portions 9 at their lower ends for the passage of suitable fastening devices, and whereby said standards or legs may be suitably secured in position upon the vessel. The legs of each set are connected and pressed by cross pieces 10, and the two sets of legs are united by longitudinal bars 11. The bars 11 have their upper surfaces arranged to lie flush with the upper end of the cradle forming portion 7, so that the bracket pieces 3 of the body 1 may rest thereon when said body 1 is seated in the cradle to support the same firmly in position.

For the purpose of fastening the body 1 against displacement, a stationary fastening member 12 is provided at one end of the frame, which fastening member is formed with a rigid detent 13 to engage the adjacent flange or chine 2, where at the opposite end of the frame is provided a latch 14 of bell crank form, one of the arms of which is provided with a detent or engaging member to engage the other chine or end flange 2 of the body 1. The latch is pivotally mounted upon the frame, as indicated at 16, and to its other arm is connected a rod 17 whereby the latch may be retracted to allow the barrel to float free when submerged for ascension to the surface.

In practice, the buoyant body 1 may be mounted in any suitable or convenient position upon the top of a submarine vessel 18, or upon the deck or other portion of an ordinary vessel, and the rod 17, in the case of a submarine vessel, may extend downwardly into the body of the vessel through a stuffing box, or in the case of an ordinary vessel the rod may extend into a cabin or be otherwise arranged for convenient manipulation when required.

Journalized upon the lower cross piece 10 is a shaft 19 carrying a drum or reel 20 with which is connected one end of a cable 21, the opposite end of which is connected with the buoyant body 1 by means of a swivel, as indicated at 22. The cable may be of any suitable length, and when the buoyant body is freed and rises to the surface of the water the cable unwinds from the drum or base until the buoyant body reaches the surface. The buoyant body is thus prevented from drifting away, and will indicate upon the surface substantially the position of the

vessel, while the cable leading therefrom will indicate the exact position of the vessel, enabling aid to be afforded to a sunken submarine which can not arise or the location of an ordinary sunken vessel to be determined with certainty and reliability.

It will thus be seen that my invention provides a means whereby a buoyant body may be released from a submarine unable to arise to the surface, or from a surface vessel which is sinking, in order to indicate the position of such vessel, and that if desired a written message, documents or other articles may be inclosed within the buoyant body to be carried to the surface, to advise a rescuing vessel of conditions below to enable valuables to be sent to the surface for recovery and preservation.

While the structure disclosed is preferred, it will of course be understood that modifications within the spirit and scope of the appended claim may be made without departing from the invention.

I claim:

15. A device of the character described comprising a supporting frame consisting of

pairs of end standards, the standards of each pair being arranged to converge in an upward direction and having partly circular portions extending therefrom in opposing relation, cross pieces uniting the standards of each pair, longitudinal pieces connecting the partly circular extensions of the pairs of standards and forming a substantially semi-circular cradle, a retaining member carried by the cross pieces at one end of the frame, a buoyant body adapted to rest in said cradle and having end flanges, one of said flanges being adapted for engagement with said retaining member, a latch upon the opposite end of the frame for engagement with the other flange of the buoyant body, means for operating the latch, a drum journaled upon the frame, and a cable connecting the buoyant body with said drum.

In testimony whereof I affix my signature in presence of two witnesses.

CHARLES M. ROLLO.
